(57) CLAIM

The ornamental design for a radio transmitter which is connectable to a computer or an MP3 player device, as shown and described.

DESCRIPTION

FIG. 1 is a perspective view of a radio transmitter showing my new design;

FIG. 2 is top view thereof;

FIG. 3 is a front elevational view thereof;

FIG. 4 is a side elevational view thereof as seen from the left in FIG. 3;

FIG. 5 is a side elevational view thereof as seen from the right in FIG. 3;

FIG. 6 is a rear elevational view thereof; and,

FIG. 7 is a bottom plan view thereof.
